ROTOR FOR MULTISTAGE AXIAL FLOW
COMPRESSORS AND TURBINES

Leslie Thomas Whitehead, Farnborough, England,
assignor to Power Jets (Research and Development) Ltd., London, England, a British company

Application October 5, 1945, Serial No. 620,503
In Great Britain October 6, 1944

8 Claims. (Cl. 230—134)

1

This invention relates to rotors for multi-stage axial flow compressors and turbines.

It is usual to provide multi-stage compressors of the axial flow type with a rotor comprising either a hollow drum or a plurality of solid discs. With the drum type rotor the maximum centrifugal stress is approximately twice that in a solid disc of uniform thickness for the same rim speed. If the disc is bored for a central shaft, the stress approaches that of a hollow drum unless the disc thickness is increased toward the centre, thereby increasing the weight. Also, when calculating whirling speed for a disc rotor the shaft diameter is used and not the rim diameter; this results in a much lower critical speed than for a drum rotor with similar bearing centres.

Now the object of the present invention is to provide a multi-stage rotor of simplified construction which will have the advantages of the solid disc, so far as centrifugal stress is concerned, and of the hollow drum insofar as it has a comparatively high critical speed and large effective diameter.

According to the invention, the multi-stage axial flow compressor or turbine rotor comprises a plurality of solid discs which are coaxially arranged and are directly interconnected at their rims so that the latter jointly afford the equivalent of a hollow drum blading being secured in axial grooves in the drum-like assembly and elements in the axial grooves extending across the joints between the discs which are thereby locked against relative rotation. The elements extending across the joints may be in the form of spacers between the blade roots or the blade roots themselves may serve as such elements.

In order that the invention may be clearly understood and readily carried into effect, the same will now be more fully described with reference to and by the aid of the accompanying drawings, in which—

Fig. 1 is a diametrical section of the rotor drum of a multi-stage axial flow compressor (or turbine) constructed according to one embodiment of the invention.

Fig. 2 is a fragmentary section, on an enlarged scale, illustrating more clearly the manner in which the rims of adjacent disc elements of the rotor drum are mated and secured together.

Fig. 3 is a similar view to Fig. 2 but illustrating a modification.

Figs. 2 and 3 also illustrate the mounting of the blades in axially disposed grooves and the

2

employment of spacers between blades of adjacent rows.

Figure 4 is a section taken along the line 4—4 of Figure 2.

5 Referring to the embodiment shown in Fig. 1, the drum comprises a series of solid discs 1 each of which increases in thickness toward the centre and is formed integrally with rim flanges 2, 3 which extend one to each side of the disc. 10 The discs 1 are arranged co-axially and the opposed rim flanges 2, 3 of adjacent discs are adapted to be passed into overlapped engagement and to be secured together by mating screw threads 4 as shown. Thus, as illustrated more clearly in Fig. 2, the rim flanges 2, 3 of each disc 1 are screw threaded, one internally and the other externally, to mate with complementary screw threaded rim flanges of adjacent discs 1. In this connection the flanges 2, 3 are stepped or 15 rebated, one internally and the other externally, and the screw threads 4 are cut in the circumferential surfaces of the rebates and extend over the whole of the length thereof. Alternatively, as shown in Fig. 3, only a part of the circumferential surfaces of the rebates in the rim flanges are threaded and the remaining plain portions of said surfaces afford a well-fitting spigot and socket when the rim flanges of adjacent discs are screwed together in overlapped 20 relation. In this latter connection, the plain or unthreaded portions of the circumferential surfaces of the rebates may be tapered or coned so that when the rim flanges of adjacent discs are screwed up tightly together in overlapped relation the mating plain circumferential surfaces of the rebates will bind to ensure an even more intimate spigot and socket connection.

When assembling the multi-stage rotor by screwing the rim flanges of adjacent discs one into another, advantage may be taken of the working temperature difference between stages, or the temperature drop along the rotor, by arranging that the internally threaded rim flange of a cooler disc overlaps on the outside the externally threaded flange of a hotter disc, thereby ensuring that any differential expansion will tend to keep the screw-thread joint tight.

Assembly of the disc elements to constitute a combined disc and drum rotor would be effected before finally machining the outer diameter and cutting the blade grooves. Each disc 1 may carry a circumferential row of radially disposed blades 5, as shown, mounted in serrated axially disposed grooves, said grooves, indicated at 6, 45 may be cut throughout the length of the rotor

drum and the blades of adjacent rows be located by serrated spacers 1 inserted in said grooves 6 and arranged to bridge the screwed joints between adjacent disc elements so as to constitute keys locking the rims of adjacent discs together against relative rotation or unscrewing.

In Fig. 1 an axially disposed shaft coupling 8 is mounted on one of the end discs of the composite rotor and a hollow shaft extension 9 is screwed into the outermost rim flange 2 of the other end disc.

It will, of course, be understood that whereas in the embodiments illustrated the serrated type of blade root fixing is shown, the sides of the blade roots and of the intermediate spacers 1 being serrated to cooperate with complementary or corresponding serrated side walls of the grooves 6, any other conventional or convenient method of blade fixing and locating may be employed in conjunction with axial grooves in the rotor.

What I claim as my invention and desire to secure by Letters Patent is:

1. A rotor for a multi-stage axial flow turbo-machine, comprising in combination, a series of solid discs arranged coaxially with their rims abutting and jointly affording the equivalent of a hollow drum, blading secured in axial grooves in said drum-like assembly of inter-connected discs, and elements in said grooves extending across the joints between said discs thereby locking said discs against relative rotation.

2. A rotor for a multi-stage axial flow turbo-machine comprising in combination a series of solid discs arranged coaxially and formed integrally with rim flanges on opposite sides, the opposed rim flanges of adjacent discs being secured together in overlapped engagement, blading secured in axial grooves in said discs, and elements in said grooves extending across the joints between said discs thereby locking said discs against relative rotation.

3. A rotor for a multi-stage axial flow turbo-machine comprising in combination a series of solid discs arranged coaxially and formed on opposite sides with integral rim flanges which are screw-threaded, one internally and the other externally, the opposed rim flanges of adjacent discs being secured together in overlapped engagement by screwing one into the other, blading secured in axial grooves in the rims of said discs, and elements in said grooves extending across the joints between said discs thereby locking said discs against relative rotation.

4. A rotor for a multi-stage axial flow turbo-machine, comprising in combination a series of solid discs arranged coaxially and formed on opposite sides with integral rim flanges which are rebated, one internally and the other externally, the circumferential surfaces of the rebates being screw-threaded, the opposed rim flanges of adjacent discs being secured together in overlapped engagement by screwing one into the other, blading secured in axial grooves in the rims of said discs, and elements in said grooves extending across the joints between said discs thereby locking said discs against relative rotation.

5. A rotor for a multi-stage axial flow turbo-machine, comprising in combination a series of solid discs arranged coaxially and formed on opposite sides with integral rim flanges which are rebated, one internally and the other ex-

ternally, portions of the circumferential surfaces of the rebates being screw-threaded, the opposed rim flanges of adjacent discs being secured together in overlapped engagement by screwing the externally threaded portion of one into the internally threaded portion of the other with the plain portions of the rebates mating to afford spigot and socket connections, blading secured in axial grooves in the rims of said discs, and elements in said grooves extending across the joints between said discs thereby locking said discs against relative rotation and at the same time spacing said blading.

6. A rotor for a multi-stage axial flow turbo-machine, comprising in combination a series of solid discs arranged coaxially and formed on opposite sides with integral rim flanges which are screw-threaded, one internally and the other externally, the opposed rim flanges of adjacent discs being secured together in overlapped engagement by screwing one into the other, radially disposed blades mounted in serrated axial grooves in the assembly of disc rims and arranged in circumferential rows, and serrated spacers in said axial grooves between and locating said blades and bridging the screwed joints between adjacent disc rims, said spacers thereby constituting keys which lock the rims of the discs against relative rotation.

7. A rotor for a multi-stage axial flow turbo-machine, comprising in combination a series of solid discs arranged coaxially and formed integrally with rim flanges on opposite sides, the opposed rim flanges of adjacent discs being secured together in overlapped engagement with the rim flanges of a cooler disc overlapping on the outside the rim flange of the adjacent hotter disc, whereby any differential expansion keeps the joint between the overlapped flanges tight, blading secured in axial grooves in the rims of the said discs, and elements in said grooves extending across the joints between said discs, thereby locking said discs against relative rotation.

8. A rotor for a multi-stage axial flow turbo-machine, comprising in combination a series of solid discs arranged coaxially and formed on opposite sides with integral rim flanges which are screw-threaded, one internally and the other externally, the opposed rim flanges of adjacent discs being secured together in overlapped engagement by screwing one into the other, the internally threaded rim flange of a cooler disc overlapping the externally threaded rim flange of the adjacent hotter disc whereby any differential expansion keeps the screw-threaded joint tight, blading secured in axial grooves in the rims of said discs, and elements in said grooves extending across the joints between said discs thereby locking said discs against relative rotation.
